MATTRESS

Irving Weisglass, New York, N. Y., assignor to
United States Cabinet Bed Co., Brooklyn, N. Y.,
a corporation of New York

Application October 14, 1942, Serial No. 461,937

2 Claims. (Cl. 5—355)

This invention relates to mattresses in general and more particularly to mattresses having a fibrous filler such as felt or the like.

Among the objects of the present invention, it is aimed to provide an improved mattress having a fibrous filler such as layers of felt or the like and means for anchoring the filler against displacement and also to distribute the felt in predetermined different quantities throughout the mattress and anchor such predetermined different quantities against displacement in order to protect a mattress from the distortion in use resulting in the displacement of the fibrous elements from the center or middle of the mattress to either side thereof.

It is another object of the present invention to provide an improved mattress consisting of a fabric envelope or enclosure initially composed of upper and lower fabric layers, transversely extending fabric partitions secured to the upper and lower layers to form transversely extending pockets, rolls of felt layers positioned in such pockets, an endless fabric border, and endless tape edging strips folded over and secured to the edges of said endless fabric border and to the adjacent edges of said upper and lower fabric layers.

It is still another object of the present invention to provide an improved mattress consisting of a fabric envelope or enclosure composed of upper and lower fabric layers, transversely extending fabric partitions secured to the upper and lower layers at predetermined varying distances from one another dividing the mattress into four narrow pockets, two at each end of about five inches in width, four wide medially located pockets of about eight inches in width, and four intermediately located pockets of about six inches in width, two of the intermediately located pockets disposed between the medially located set and each end set, with the partition fabrics also varying in depth so that each of the medially located pockets may effectively receive a roll of felt layer weighing about eleven pounds, each narrow end pocket receiving a roll of a felt layer weighing about six pounds and each intermediate pocket receiving a roll of a felt layer weighing about eight pounds.

It is still another object of the present invention to provide an improved method for forming a mattress having upper and lower fabric layers, transversely extending partitions to form pockets, positioning rolls of felt into each pocket so formed, thereupon positioning an endless fabric

border strip between the upper and lower fabric layers, and securing endless tape edging strips, one to the edge of the upper layer and to the upper edge of the border strip and the other to the edge of the lower layer and to the lower edge of the border strip effectively to secure the rolls of felt in pockets formed between the upper, lower and border layers.

These and other features, capabilities and advantages of the invention will appear from the subjoined detail description of one specific embodiment thereof illustrated in the accompanying drawing in which

Figure 1 is a plan of the improved mattress.
Fig. 2 is a fragmental transverse section on the line 2—2 of Fig. 1.

Fig. 3 is a fragmental perspective of a roll of felt.

Fig. 4 is an exploded view of the improved mattress before being assembled.

In the embodiment shown, the mattress 1 consists essentially of an envelope or enclosure including the upper fabric layer 2, the lower fabric layer 3, the endless fabric border 4, and two endless tape edging strips 5 and 6. The fabric of the layers 2 and 3 and border 4 is preferably of the type generally known as mattress ticking and the tape edging strips 5 and 6 may be made of the same material or some other suitable tough and durable fabric.

In the course of manufacture, the layers 2 and 3 are preferably first measured to locate the positions for attachment of the partitioning fabrics 7 which are also preferably composed of a suitable tough and durable material such as mattress ticking. With a mattress of about 76 inches in length by about 39 inches in width, it has been found expedient and practical to form at least twelve compartments or pockets.

According to the present invention it is one object thereof to position or locate against displacement a larger amount, and preferably the largest amount of the felt filler in the middle of the mattress where it is ordinarily subjected to the greatest pressure heretofore resulting in the objectionable depressions so frequently present in the middle of mattresses composed of felt or the like filling material after such mattresses have been used for any material length of time. Such depressions are mainly formed as a result of the filling material gradually spreading away from the location of greatest pressure, the middle of the mattress. Another cause for the formation of these depressions resides in the fact that the filling material if composed of fibrous matter

such as felt will become more compact in the middle than in the other parts of the mattress which are not subjected to the pressures to which the middle of the mattress ordinarily is subjected.

By dividing the mattress into twelve compartments and isolating a predetermined quantity of filler in each compartment, in part at least, the formation of the depressions is minimized, if not entirely eliminated. According to the present invention, however, the middle compartments are made the largest, the end compartments are made the smallest and the other compartments or pockets between the smallest and the largest graduate in size from one to the other, and predetermined different amounts of filler are introduced into each pocket corresponding to the size thereof.

When as aforesaid the length of the mattress is about 76 inches and the mattress is divided into twelve compartments, then as one example of the proportions that have been found to give excellent results, it is desirable that the end compartments 8 are about five inches in width, the intermediate compartments 9 about six inches in width and the four middle compartments 10 about eight inches in width. The heights of these several compartments also vary somewhat to correspond to their respective widths.

The four middle compartments 10 are disposed adjacent to one another, the two end compartments 8 are disposed at each end of the mattress, and the two intermediately sized compartments 9 are disposed between each set of end compartments 8 and the middle set of compartments 10 as shown in Fig. 1.

If the cushion forming or cushioning filler is composed of felt, preferably it is prepared in layers and rolled up into a roll such as the roll 11 of Fig. 3. The amount of filler used is preferably determined by weight. When the filler is felt, then it has been found desirable to distribute the weight as follows: the filler for each end pocket 8 to approximate about six pounds, the filler for each intermediate pocket 9 to approximate about eight pounds and the filler for each middle pocket 10 to approximate about eleven pounds.

With mattresses of this type it has been found that considerable time in labor can be saved in production when the upper and lower layers 2 and 3 are first measured for their sub-divisions and then the fabric partitions 7 of predetermined and varying height secured to the layers 2 and 3 to form the pockets required. Then the layers of felt measured as to weight and rolled up into rolls such as the rolls 11 illustrated in Fig. 3 and introduced into the several pockets 8, 9 and 10, the heavier eleven pound rolls 11 introduced into the pockets 10, the intermediate eight pound rolls 11 into the pockets 9 and the lightest six pound rolls 11 into the pockets 8.

Thereupon the border fabric 4 with its ends secured to one another to form an endless border is positioned around the edges of the mattress so

far formed, between the upper and lower layers 2 and 3 and then the endless tape edging strips 5 and 6 also formed into endless strips by securing the ends of each to one another, and thereupon folded over adjacent edges of the border 4 and layers 2 and 3. In other words, the strip 5 is folded over the edge of the layer 2 and the upper edge of the border 4 and then preferably machine stitched into place, and the strip 6 folded over the edge of the layer 3 and the lower edge of the border 4 and then preferably machine stitched into place.

Preferably as shown the outer end 13 of each felt layer 12 is cut into a tapered edge to form a smooth finished roll 11.

It is obvious that various changes and modifications may be made to the details of construction and to the steps of the method without departing from the general spirit of the invention as set forth in the appended claims.

I claim:

1. The combination of upper and lower fabric layers, transversely extending fabric partitions of different widths diminishing in width from the greatest at the middle to the narrowest at the ends connecting said upper and lower fabric layers to one another to form a plurality of transversely extending pockets of different widths diminishing in width from the greatest at the middle to the narrowest at the ends, filler forming rolls of different diameters graduating in diameter disposed in each of said pockets with the largest in the middle pocket and the smallest at the ends conforming to the pockets, a pre-formed endless border fabric having smooth uninterrupted corners and having end portions conforming to the sides of the end pockets and side portions gradually diminishing toward their ends to conform to the ends of the fillers and pockets to position not only the fillers in their pockets but also to register with the edges of said upper and lower layers, two endless tape edging strips, one of said tape edging strips folded and secured to the edge of said upper layer and to the adjacent upper edge of said border layer, and another of said tape edging strips folded and secured to the edge of said lower layer and to the adjacent lower edge of said border layer.

2. The method of forming mattresses consisting in securing a plurality of vertically extending fabric partitions to upper and lower fabric layers to form transversely extending pockets, introducing filler rolls into place in each of said pockets, then slipping an endless border around the exposed edges and sides of the pockets and filler rolls thereby to position its upper and lower edges adjacent to the edges of the upper and lower layers, and then securing the so positioned upper and lower edges of the endless border to the edge of the upper layer and to the edge of the lower layer respectively finally to enclose the several filler rolls.

IRVING WEISGLASS.
